METHOD OF BURNING OIL AS GAS

Filed Dec. 6, 1935

UNITED STATES PATENT OFFICE

2,162,432

METHOD OF BURNING OIL AS GAS

Charles B. Hillhouse, New York, N. Y., assignor to
Sylvia Remsen Hillhouse, New York, N. Y.

Application December 6, 1935, Serial No. 53,238

1 Claim. (Cl. 158—117.5)

My invention relates to a method for burning oil as gas, and more particularly to a method for combustion of oil or other hydrocarbon wherein a portion of the fuel to be burned, preferably in gaseous form, is caused to combust in a manner to produce hot combustible gases which are mixed at a suitable temperature with a portion of liquid hydrocarbon to gasify it, and these mixed gases may be burned with sufficient air completely at another point.

A main object of the invention is to provide a method wherein the fuel, preferably in the form of gas is burned as a preliminary step with insufficient air for complete combustion so as to produce combustible gas and, thereafter, a liquid hydrocarbon fuel is intimately mixed with the hot products of partial combustion and gas to gasify the liquid fuel mixed therewith.

Another object is to provide a method wherein the oil is gasified and maintained gasified in a suitably heated state while mixed with the gases formed by the partial combustion of a portion of the made gas until the mixture is mixed with preheated air in the burner or burners.

Another object is to provide a control of the temperature of the gases formed by partial combustion so that, when oil is sprayed into or mixed with these gases, there will be sufficient sensible heat in the gases to gasify the oil, but not enough sensible heat to cause any detrimental deposition of carbon at the time or point of mixing, particularly where the burners are situated at a considerable distance from the point of production.

This application is a continuation in part of my applications, Serial No. 756,689, filed December 8, 1934, now Patent 2,047,871 issued July 14, 1936, and Serial No. 679,767, filed July 10, 1933, Patent No. 1,987,401 issued January 8, 1935. In the present application, a portion of the made oil gas is conducted to a gasifier unit where it is partly combusted to form a hot combustible gas. I provide also a means in the form of spirally arranged cooling coils located in a manner to regulate the temperature of the hot gases of partial combustion and, thereby indirectly, the temperature at which the oil, or fuel, is gasified. Additional means are provided to maintain the gasified oil in a heated state until the gasified oil and gases of partial combustion are mixed with sufficient air in the main fuel burner. This additional means may comprise a jacket for confining air that has been preheated by proximity to the gasifier unit for the purpose of maintaining a reduced temperature thereof; and which

air, so preheated, is applied and used to maintain gasified oil in a suitably heated state by indirect heat exchange relation thereto preferably as a hot jacket around the conduit carrying the mixed gases. This preheated air is finally mixed, all or in part, into the made gases at the main burner or burners; which, owing to the transfer of heat from the heated air, may be positioned at a distance from the gasifier described. If the distance between the point of gasification and the burner is short and ample means are applied to prevent material loss of heat from the gas mixture, I may dispense with the use of the jacket.

In the accompanying drawing—

Figure 1 shows a vertical cross-section of an oil burner constructed to carry out the method described;

Fig. 2 shows a cross-section on line 2—2 of Fig. 1;

Fig. 3 shows a cross-section on line 3—3 of Fig. 1; and

Fig. 4 shows a modification.

In the preferred form of apparatus shown, a gasification chamber 1 is shown as having an outer heat insulating wall 2 and an inner refractory wall 3 spaced to provide an air conducting space 4. The portion of the made gases that is to be partially combusted, is supplied from a conduit 5 to a burner 10. A blower 6 supplies air to a conduit 7 which is connected to a conduit 8 which terminates in an air feed pipe 9 leading to burner 10. A valve 11 serves to reduce the air supply to burner 10 to produce partial combustion, that is, enough air is used to burn all the carbon in the gas to CO, but not enough air to combust the hydrogen nor make any CO₂. Air from pipe 9 draws in made gas from the gas supply conduit 5 to feed gas to burner 10.

Air from conduit 7 enters the space 4 at inlet 12 and passes upwardly around the heated wall 3 to become preheated. Air from the blower 6 passes also through a conduit 13 and valve 14 and an inlet 15 into a spirally arranged conduit 16 that surrounds the burning gas emanating from burner 10. The air in conduit 16 extracts heat from this burning gas in an amount regulated by valve 14 and heated air leaves the conduit 16 by an outlet 17 which communicates with space 4.

The preheated air in space 4 passes upwardly and is conducted along a path to surround the gas outlet conduit, being confined in a space 18 formed between a conduit 19 and a wall 20. The

gases from chamber 1 pass upwardly through an outlet throat 21 into the conduit 19. The oil for gasification is supplied from a pipe 22 and is sprayed into the throat 21 by means of an oil injecting device 23, which is controlled by the valve 24.

Oil sprayed into the throat 21 is gasified and is maintained in a gasified state by indirect transfer of heat thereto from the heated air in the space 18, which air functions as a heated transfer medium, hence this oil gas may be efficiently conducted an appreciable distance from the chamber 1 to burners 25 or 26. Heated air from the space 18 is supplied to the burner 25 through air port 27 and the oil gas is supplied through the gas port 28.

The air passing through the spiral conduit 16 serves to absorb excess heat from the gases of partial combustion in the chamber 1 before the oil fuel is sprayed into these gases at the throat 21 so that the mixture may be reduced in temperature. The temperature of the gases and gasified oil admitted to the conduit 19 is so regulated that the mixture will have a temperature of about 600 degrees F. or below a temperature at which there will be any deposit of carbon. The conduit or chamber 19 is, in effect, separate from the combustion chamber 1, and may be structurally associated with the latter in any desired manner providing that hot gases generated in the latter may be passed into the chamber 19, to gasify oil sprayed thereinto.

In order to maintain a complete gas cycle, my invention includes the feature of returning un-consumed gas from the burners to the point where the new oil-gas is being formed. To accomplish this purpose, the excess gas is drawn off at a point adjacent the burner through an outlet 29 into a return conduit 30 and is discharged at an outlet nozzle 31 into the gas stream that enters conduit 19. A pump 32 may be used in conduit 30 to facilitate the passing of a portion of gas to the burner 10 and the return of the balance of this unused gas to conduit 19.

In Fig. 4, the gas return conduit 30 is shown as enclosed within the jacket wall 20 in a manner to maintain the temperature of the returned gas substantially equal to the temperature of the gas in the conduit 19.

A pilot burner 33 is provided to initially start the gas cycle. Gas or oil is supplied to pilot 33 from a conduit 34 controlled by a valve 35. Air is supplied to the pilot burner 33 from a branch air conduit 36 and air feed is controlled by a valve 37. Fuel and air feed to burner 33 is varied by valves 35 and 37 in a manner to provide incomplete combustion of this fuel to produce a hot combustible gas. When the chamber 19 is full of made gas, pilot 33 may be cut out and burner 10 started.

In the operation of my device, a portion of the made gas is supplied to burner 10 and air in regulated amounts from air inlet. This gas is partially combusted, that is, the air is in insufficient amount to combust the hydrogen or make any CO₂, although all of the carbon is burned to form CO. The mass of burning gas is indicated by dotted lines A—B. Air from conduit 13 is forced through the spiral conduit 16 to be preheated and extract heat from the hot gases of partial combustion. This air is then passed into space 4 and out of the gas generator and into the space 18 to flow along the conduit 19. There is little or no interchange of heat between the hot air

jacket and the made gases when not over 200 degrees F. difference in temperature exists between them and when only a short time has elapsed for transfer of the gas to the burner. Oil from conduit 22 is sprayed into the throat 21 and is gasified and is maintained in that form due to the stabilizing action of heated air in the space 18 surrounding this gas. This heated air all or in part, in turn, is supplied to the burners to support combustion of made gases admitted from the fuel passage 28.

The temperature to be aimed at for the mixture of sprayed oil and gases of partial combustion should be about 600 degrees F. so as to be secure from any carbon deposition. To prevent any breakdown of the unstable oil gases before reaching the burner 25, the pipe 19 conveying the above mixture is encased in another pipe 20 making a double shell. The hot air between these shells is maintained at about 450 degrees F. Due to the relation of made oil gas and heated air and the stabilizing action of the heated air upon the temperature of the oil gas, the oil gas may be conveyed to a burner or burners located at some distance from the gasifier without appreciable change in character of the generated oil gases. One of the essential features of this apparatus is to control the temperature of the gases of partial combustion so that when oil is sprayed into them, there will be enough sensible heat in the gases to gasify the oil but not enough to cause any deposition of carbon. This is brought about by the cooling effect of the air which is passed through the spiral conduit 16.

This gasification does not make a fixed gas but the gas or gases are permanent so long as they are kept at a temperature sufficiently high to prevent their reversion in part to liquid form. For instance, gasoline is a gas at its temperature of distillation but at atmospheric pressure and normal temperature it is in liquid form. When I apply generated hot combustible gas to a spray of oil, when the resulting or final temperature is about 650 degrees F., I gasify the oil and not merely vaporize it. I propose also to keep that latter gas at a temperature above its reversion point, and burn a mixture of true gases in the burners, though it is not necessarily a mixture of fixed gases at atmospheric pressure and normal temperature.

The temperature of the hot gases of partial combustion may be from 900 degrees to 1000 degrees F. at the place of spraying oil into same, but the temperature of conversion or lowest temperature after production of the mixture of gases will be not over about 650 degrees, whereby there will be no tendency to produce deposition of carbon as might occur at higher temperatures than 650 degrees F.

I claim:

A method of burning oil which consists in reducing by partial combustion a portion of combustible gas to form carbon monoxide and hydrogen and other gases, spraying into said last-named gases, while heated, a portion of oil to produce fuel gases, applying sufficient heat to the fuel gases prior to burning the same to prevent any reversion of gas to a liquid form, burning the major portion of heated fuel gases with air for complete combustion and diverting the remaining portion of the heated fuel gases to flow partly into the stream of said last-named gases and partly to the zone of partial combustion.

CHARLES B. HILLHOUSE.
